PAPER CONTAINER.

Application filed April 24, 1920. Serial No. 376,400.

The present invention relates to paper containers, that is, to containers made of any suitable fibrous stock, whether paper or resembling paper, and particularly to the 5 neck and the cap fitted therein. The container may be in the form of a can with a cylindrical side wall, or in any suitable polygonal or curved form, wound or formed in any suitable way and having a bottom 10 seal of any suitable kind. The paper stock may be single or multiple ply with or without incorporating a binder, and the container may be coated with paraffine or the like and may have a paper covering or advertising label.

I have found it desirable to provide a seat or ledge projecting a considerable distance inwardly of the side wall of the container, for otherwise the cap is often pushed into 20 the contents in sealing the container. In accordance with this part of my invention, the neck, reenforced for strength and formed from a continuation of the side wall so as to be integral therewith, has a ledge which projects sufficiently inwardly of the side wall to form a seat that not only supports the cap over an extended area but practically insures that the cap will not be pushed into 25 the contents. For this purpose the ledge is formed of a plurality of folded portions, preferably of two, the terminal portion being enclosed between the other portions with its end surface covered thereby or in contact therewith so as to prevent capillary attraction through its raw edge. In the preferred 30 embodiment hereinafter described these folded portions comprise a base portion, an intermediate portion, and a terminal portion folded upwardly between the base and intermediate portions; the intermediate portion having a horizontal part and the terminal portion extending into contact therewith to 35 form the ledge. So also, in this embodiment, the reenforced neck has a cap-retaining 40 groove formed by an outwardly bulging part, and the ledge projects inwardly of the side wall in uninterrupted conformity with the lower surface thereof to further extend the seating surface. Preferably the cap, 45 seated in the groove and on the ledge, is, in order to more effectively seal the container, gripped on its upper surface by the upper edge of the groove, which extends outside of the upper edge of the side wall to facilitate 50 the fitting of the cap in the groove. Further

than the advantages pointed out above, this specific form of construction compensates nicely for changes in gage dimensions, due to manufacturing inaccuracies and to expansion and contraction of the blanks before 60 they are formed into containers, for the ledge may extend to any required depth within the container.

Whether or not the container has a neck of the foregoing form, but preferably so, the 65 invention comprehends as another of its parts a paper container in which the upper part of the neck is turned over against the top surface of the cap to tightly seal it therein after filling. Thus, before filling, 70 the container comprises an upstanding neck which is of a height sufficient to be turned over against the cap, the intention being that the container be supplied to the packer with the neck upstanding, and that the 75 packer turns over the neck to seal the contents. In the specific embodiment herein-after described, the terminal part of the neck is enclosed within the folds of the turned over upper portion and preferably extends 80 upwardly into contact with another part thereof so that the possibility of the ingress and egress of moisture or foreign matter between the folds is minimized. In fact this part, turned over against the upper surface 85 of the cap, is highly compressed and practically solidified to form a rigidly set bead, so that the container is securely closed particularly where the cap is gripped between the upper and lower edges of the cap-retaining 90 groove. Where the previously mentioned ledge, on which the cap is seated, is also highly compressed and practically solidified into rigidly set form, the cap is substantially hermetically sealed in the neck of 95 the container almost indefinitely.

Although the container may have any suitable form, I prefer the form of a firkin wherein the side wall flares upwardly, for then the containers, without the caps, may 100 be nested in shipment to the packer. Furthermore, by varying the pressure applied, the ledge on which the cap is seated is made thicker at the top than at the bottom, or gradually decreased in thickness toward the 105 bottom, or in fact may have its outer surface in contact with the tapering side wall while its inner surface is substantially vertical, to thereby produce a more effective seat for the cap while preventing the passage of mois- 110

ture or liquids from the contents between the folds forming the reenforced neck. The pressure to which the reenforced neck is subjected in forming it, is made possible by the added stock of the folds.

In the accompanying drawings illustrating the preferred embodiment of the invention in application, as an example, to a firkin of single ply stock, having a hermetically sealed bottom,

Fig. 1 is an elevation, partially in section and partly broken away in full view, of the container with the neck upstanding as before sealing; Fig. 2 is an enlarged sectional detail of the upstanding neck with the cap fitted therein; Fig. 3 is a view similar to Fig. 1 but with the upper part of the neck turned over; and Fig. 4 is an enlarged sectional detail thereof with the neck shown upstanding in broken lines.

The container has an upwardly flaring side wall 1 of paper stock of suitable thickness and surface finish, and a hermetically sealed bottom closure 2 formed by so interlocking and compressing folded portions of a continuation of the side wall with folded portions of the bottom member 3 as to rigidly set them against penetration and against upward and downward pressure.

The reenforced neck is formed from a continuation of the side wall and comprises a base portion 4, an intermediate portion 5, and an abbreviated terminal portion 6 folded upwardly between the base and intermediate portions, so as to have its outer surface in contact at 7 with the base portion and its inner surface in contact at 8 with the intermediate portion. The neck has a cap-retaining groove 9 formed by an outward bulge at 10 of the base and intermediate portions, and the intermediate portion has a horizontal part 11 extending inwardly of the side wall in uninterrupted conformity with the lower surface of the groove. The peripheral surface of the terminal portion 6 is in contact at 12 with the underside of the horizontal part 11 so as to prevent capillary attraction of contents of the container through the raw edge of the paper stock with the consequent contamination and change of the contents. The intermediate portion forms with the terminal portion a ledge 13, which has its inside surface at 14 substantially vertical so as to form an extended seating surface for a suitable paper cap 15. Not only does the ledge extend inwardly of the side wall for a sufficient distance to provide a suitable seat for the cap, but it also prevents the cap from being pushed readily into the contents when sealing the container. Furthermore, although the cap is held against that seat by the upper edge 16 of the groove, that edge lies outside of the upper edge of the side

wall to enable the cap to be readily fitted in place for sealing.

In order that the neck, and particularly the ledge 13, may be rigidly set to permanent gage dimensions, those parts are preferably subjected, in forming, to a pressure of from 4,000 to 6,000 pounds per square inch. The lower part of the ledge is compressed more than the upper part to bring the inner surface thereof substantially vertical and also to force more intimately into contact with each other the lower parts of the ledge and base portion to thereby more effectively exclude the seepage of the contents of the container between the folds of the neck.

The firkins are intended to be shipped to the packer in the form shown in Fig. 1, the cap 15 being removed to permit nesting. After a container is filled, the upper part of the neck is turned over against the upper surface of the cap into a highly compressed, practically solidified and rigidly set bead 17, hermetically sealing the cap in place with the terminal part 18 folded upwardly into contact with another part and enclosed therebetween to prevent the ingress or egress of moisture or foreign matter between the folds of the bead.

A sealed container of this kind, filled with liquids or solids, such as molasses, cheese, etc., may be transported without hazard, and maintain its dimensions and hermetical closure almost indefinitely. Still the container may be readily opened to consume the contents by cutting away the cap 15.

Having thus described my invention, what I claim is:

1. In a paper container; a side wall; a bottom closure therefor; a reenforced neck formed from a continuation of the side wall and having a ledge projecting inwardly thereof and formed of a plurality of folded portions including a terminal portion enclosed between the other portions; and a cap seated on said ledge.

2. In a paper container; a side wall; a bottom closure therefor; a reenforced neck formed from a continuation of the side wall and having a ledge projecting inwardly thereof and formed of a plurality of folded portions including an upwardly extending terminal portion enclosed between the other portions; and a cap seated on said ledge.

3. In a paper container; a side wall; a bottom closure therefor; a reenforced neck formed from a continuation of the side wall and comprising a base portion, an intermediate portion, and a terminal portion folded upwardly between the base and intermediate portions, said intermediate and terminal portions forming a ledge projecting inwardly of the side wall; and a cap seated on said ledge.

4. In a paper container; a side wall; a bottom closure therefor; a reenforced neck formed from a continuation of the side wall and comprising a base portion, an intermediate portion, and an abbreviated terminal portion folded upwardly between the base and intermediate portions and terminating underneath the intermediate portion, said intermediate and terminal portions forming a ledge projecting inwardly of the side wall; and a cap seated on said ledge. 70
5. In a paper container; a side wall; a bottom closure therefor; a reenforced neck formed from a continuation of the side wall and having a horizontal part forming a ledge projecting inwardly of the side wall with a terminal portion extending upwardly underneath the horizontal part; and a cap seated on said ledge. 80
6. In a paper container; a side wall; a bottom closure therefor; a reenforced neck formed from a continuation of the side wall and having a horizontal part forming a ledge projecting inwardly of the side wall with a terminal portion extending upwardly into contact with the horizontal part; and a cap seated on said ledge. 85
7. In a paper container; a side wall; a bottom closure therefor; a reenforced neck formed from a continuation of the side wall and comprising a base portion, an intermediate portion having a horizontal part projecting inwardly of the side wall, and a terminal portion folded upwardly between the base and intermediate portions to form a ledge with the latter; and a cap seated on said ledge. 95
8. In a paper container; a side wall; a bottom closure therefor; a reenforced neck formed from a continuation of the side wall and comprising a base portion, an intermediate portion having a horizontal part projecting inwardly of the side wall, and an abbreviated terminal portion folded upwardly between the base and intermediate portions and terminating underneath the intermediate portion to form a ledge therewith; and a cap seated on said ledge. 105
9. In a paper container; a side wall; a bottom closure therefor; a reenforced neck formed of folded portions of a continuation of the side wall, said neck having a cap-retaining groove formed by an outwardly bulging part and having a ledge projecting inwardly of the side wall in uninterrupted conformity with the lower surface of the groove; and a cap seated in said groove and on said ledge. 110
10. In a paper container; a side wall; a bottom closure therefor; a reenforced neck formed from a continuation of the side wall and comprising a base portion, an intermediate portion having a horizontal part projecting inwardly of the side wall, and a terminal portion folded upwardly between the base and intermediate portions to form a ledge projecting inwardly of the side wall in uninterrupted conformity with the lower surface of the groove; and a cap seated in said groove and on said ledge. 125
11. In a paper container; a side wall; a bottom closure therefor; a reenforced neck formed of folded portions of a continuation of the side wall, said neck having a cap-retaining groove formed by an outwardly bulging part and having a ledge projecting inwardly of the side wall in uninterrupted conformity with the lower surface of the groove; and a cap seated in said groove and on said ledge and being gripped on its upper surface by the upper edge of said groove. 130
12. In a paper container; a side wall; a bottom closure therefor; a reenforced neck formed of folded portions of a continuation of the side wall, said neck having a cap-retaining groove formed by an outwardly bulging part of the neck and also having a ledge projecting inwardly of the side wall in uninterrupted conformity with the lower surface of the groove; and a cap seated in said groove and on said ledge; the upper edge of said cap-retaining groove being outside the upper edge of the side wall. 135
13. In a paper container; a side wall; a bottom closure therefor; a reenforced neck formed from a continuation of the side wall and comprising a base portion, an intermediate portion, and a terminal portion folded upwardly between the base and intermediate portions; and a cap fitted in said neck; the upper part of the neck being turned over against the top surface of the cap. 140
14. In a paper container; a side wall; a bottom closure therefor; a reenforced neck formed of folded portions of a continuation of the side wall and having a cap-retaining groove; and a cap seated in said groove; the upper part of the neck being turned over against the top surface of the cap. 145
15. In a paper container; a side wall; a bottom closure therefor; a reenforced neck formed of folded portions of a continuation of the side wall and having a cap-retaining groove; and a cap seated in said groove and gripped between the upper and lower edges thereof; the upper part of the neck being turned over against the top surface of the cap. 150
16. In a paper container; a side wall; a bottom closure therefor; a reenforced neck which is formed of folded portions of a continuation of the side wall and which has a ledge projecting inwardly of the side wall; and a cap fitted in said neck and seated on said ledge; the upper part of the neck being turned over against the top surface of the cap. 155

17. In a paper container; a side wall; a bottom closure therefor; a reenforced neck formed of folded portions of a continuation of the side wall, said neck having a cap-retaining groove formed by an outwardly bulging part and also having a ledge projecting inwardly of the side wall in uninterrupted conformity with the lower surface of the groove; and a cap seated in said groove and on said ledge; the upper part of the neck being turned over against the top surface of the cap.
18. In a paper container; a side wall; a bottom closure therefor; a reenforced neck formed from folded portions of a continuation of the side wall and having a highly compressed, practically solidified part forming a rigidly set ledge projecting inwardly of the side wall; and a cap seated on said ledge.
19. In a paper container; a side wall; a bottom closure therefor; a reenforced neck formed from a continuation of the side wall and comprising a base portion, an intermediate portion, and a terminal portion folded upwardly between the base and intermediate portions, said intermediate and terminal portions being highly compressed and practically solidified to form a rigidly set ledge projecting inwardly of the side wall; and a cap seated on said ledge.
20. In a paper container; a side wall; a bottom closure therefor; a reenforced neck formed from a continuation of the side wall and comprising a base portion, an intermediate portion, and a terminal portion folded upwardly between the base and intermediate portions, said intermediate and terminal portions being highly compressed and practically solidified to form a rigidly set ledge which projects inwardly of the side wall and which has its outer surface in contact with the side wall and its inner surface substantially vertical; and a cap seated on said ledge.
21. In a paper container; an upwardly flaring side wall; a bottom closure therefor; a reenforced neck formed from folded portions of a continuation of the side wall and having a ledge which is formed of a plurality of folded portions and which projects inwardly of the side wall; and a cap seated on said ledge.
22. In a paper container; an upwardly flaring side wall; a bottom closure therefor; a reenforced neck formed from a continuation of the side wall and comprising a base portion, an intermediate portion, and a terminal portion folded upwardly between the base and intermediate portions, said intermediate and terminal portions forming a ledge projecting inwardly of the side wall; and a cap seated on said ledge.
23. In a paper container; an upwardly flaring side wall; a bottom closure therefor;
24. In a paper container; an upwardly flaring side wall; a bottom closure therefor; a reenforced neck formed of folded portions of a continuation of the side wall and having a ledge which projects inwardly of the side wall and which has a greater thickness at the top than at the bottom; and a cap seated on said ledge.
25. In a paper container; an upwardly flaring side wall; a bottom closure therefor; a reenforced neck formed of folded portions of a continuation of the side wall and having a ledge which projects inwardly of the side wall and which has its outer surface in contact with the side wall and its inner surface substantially vertical; and a cap seated on said ledge.
26. In a paper container; an upwardly flaring side wall; a bottom closure therefor; a reenforced neck formed from a continuation of the side wall and comprising a base portion, an intermediate portion, and a terminal portion folded upwardly between the base and intermediate portions, said intermediate and terminal portions forming a ledge which projects inwardly of the side wall and which has its outer surface in contact with the side wall and its inner surface substantially vertical; and a cap seated on said ledge.
27. In a paper container; a side wall; a bottom closure therefor; a reenforced neck formed from a continuation of the side wall and comprising a base portion, an intermediate portion, and a terminal portion folded upwardly between the base and intermediate portions, said intermediate and terminal portions being highly compressed and practically solidified to form a rigidly set ledge projecting inwardly of the side wall; and a cap seated on said ledge; the upper part of the neck being turned over against the top surface of the cap and being highly compressed and practically solidified to form a rigidly set bead.
28. In a paper container; a side wall; a bottom closure therefor; a reenforced neck formed from a continuation of the side wall and comprising a base portion, an intermediate portion, and a terminal portion folded upwardly between the base and intermediate portions, said intermediate and terminal portions being highly compressed and practically solidified to form a rigidly set ledge which projects inwardly of the side wall and which has its outer surface in contact with the side wall and its inner

- surface substantially vertical; and a cap seated on said ledge; said neck having its upper part turned over against the top surface of the cap and being highly compressed and practically solidified to form a rigidly set bead. 45
29. In a paper container; an upwardly flaring side wall; a bottom closure therefor; a reenforced neck formed from folded portions of a continuation of the side wall and having a highly compressed, practically solidified part forming a rigidly set ledge projecting inwardly of the side wall; and a cap seated on said ledge; the upper part 50 of the neck being turned over against the top surface of the cap and being highly compressed and practically solidified into a rigidly set bead. 55
30. In a paper container; an upwardly flaring side wall; a bottom closure therefor; a reenforced neck formed from a continuation of the side wall and comprising a base portion, an intermediate portion, and a terminal portion folded upwardly between the base and intermediate portions, said neck 60 having a cap-retaining groove formed by an outwardly bulging part and also having a highly compressed, practically solidified part forming a rigidly set ledge which projects inwardly of the side wall in uninterrupted conformity with the lower surface of the 65 groove and which has its outer surface in contact with the base portion and its inner surface substantially vertical; and a cap seated in said groove and on said ledge; the upper part of the neck being turned over 70 against the top surface of the cap and being highly compressed and practically solidified into a rigidly set bead. 75
31. In a paper container; an upwardly flaring side wall; a bottom closure therefor; a reenforced neck formed from a continuation of the side wall and comprising a base portion, an intermediate portion, and a terminal portion folded upwardly between the base and intermediate portions, said neck 80 having a cap-retaining groove formed by an outwardly bulging part and also having a
- highly compressed, practically solidified part forming a rigidly set ledge projecting inwardly of the side wall in uninterrupted conformity with the lower surface of the groove; and a cap seated in said groove and on said ledge; the upper part of the neck being turned over against the top surface of the cap and being highly compressed and practically solidified into a rigidly set bead. 85
32. In a paper container; an upwardly flaring side wall; a bottom closure therefor; a reenforced neck formed from a continuation of the side wall and comprising a base portion, an intermediate portion, and a terminal portion folded upwardly between the base and intermediate portions, said neck 90 having a cap-retaining groove formed by an outwardly bulging part and also having a highly compressed, practically solidified part forming a rigidly set ledge which projects inwardly of the side wall in uninterrupted conformity with the lower surface of the 95 groove and which has its outer surface in contact with the base portion and its inner surface substantially vertical; and a cap seated in said groove and on said ledge; the upper part of the neck being turned over against the top surface of the cap and being highly compressed and practically solidified into a rigidly set bead. 100
33. A paper container having the edge of its body portion folded inwardly and downwardly to form the lip of the container, and having a closure-receiving seat formed by folding the inner wall inwardly, downwardly and outwardly, the material of the folds being of sufficient thickness and inherent strength to preserve the form of the closure seat, said seat constituting a ledge projecting inwardly of the side wall of the container. 105

In testimony whereof I affix my signature.
